AIRSHIP

William Wiese, Cleveland, Ohio

Application December 20, 1937, Serial No. 180,866

5 Claims. (Cl. 244—25)

This invention relates to an airship of the dirigible or lighter than air type, and has for its object to provide the ship with means in a manner as hereinafter referred to whereby the ship is propelled in a satisfactory manner and a complete control may be had at all times with respect to the lateral, ascending and descending movements of the ship.

The invention further aims to provide, in a manner as hereinafter set forth, a means for the purpose referred to which is comparatively simple in its construction and arrangement, strong, durable, readily installed, thoroughly efficient in its use, conveniently operated, readily assembled and comparatively inexpensive to set up.

To the above ends essentially and to others which may hereinafter appear, the invention consists of the novel construction, combination and arrangements of parts for the purpose aforesaid, which will be more specifically referred to and illustrated in the accompanying drawings wherein is shown an embodiment of the invention, but it is to be understood that changes, variations and modifications may be resorted to which fall within the scope of the invention as claimed.

In the drawings:

Figure 1 is a perspective view of a dirigible or airship in flight having installed therewith the means, for the purpose referred to in accordance with this invention.

Figure 2 is a front elevation of the airship shown in Figure 1.

Figure 3 is a diagrammatic view of the driving means for the propellers.

Figure 4 is a section on line 4—4, Figure 3.

Figure 5 is a top plan view of the form of wing-structures in accordance with this invention.

Figure 6 is a view looking towards the leading edge of the structure shown in Figure 5.

Figure 7 is a section on line 7—7, Figure 5.

Figure 8 is a view looking towards the trailing edge of a wing-structure.

Figure 9 is a section on line 9—9, Figure 6, and

Figure 10 is a section on line 10—10, Figure 9.

The airship is to be provided at each side of its body 1 with a set of wing-structures 2, the number of which will be as desired, preferably four and as so shown. The wing-structures of each set are disposed in staggered relation.

The wing-structures 2 of the sets are of like form and the description of one will apply to the other. Each wing-structure includes a wing body 3 of stream-lined form having its leading and trailing edges indicated at 4, 5, its tip at 6 and its root at 7. The leading edge 4 is hori-

zontally disposed and arranged substantially at right angles to that side of the body 1 from which the wing-structure extends. The wing body 3 has a rounded tip 6. The trailing edge 5 of the wing body 3 has a cutout 8 in which is arranged an aileron 9 conforming in contour to that of and corresponding in width and length to the cutout. The aileron 9 gradually increases in width from its outer to its inner side and has its trailing edge 10 flush with the trailing edge 5 of the wing body 3. The latter and the aileron 9 sets up the wing-structure as of gradually increasing width from the rounded tip 6 of wing body 4 to the root 7 of the latter. The aileron 9 has its outer side spaced from the tip 6 and its inner side spaced from root 7.

The aileron 9 is of known form and includes the transverse spars 11 which are apertured as at 12 to decrease the weight of the spars. These latter lengthwise conform in contour to the transverse sectional shape of the aileron. The latter has upstanding brace 13 to which the spars are attached. The brace 13 extends from the outer side to the inner side of the aileron. The leading edge of the latter is rounded as indicated at 14 and seats in the rounded inner wall 14^a of the cutout 8.

The wing body 4 is also provided with spars 15 and braces 16, 17 lengthwise thereof. The brace 16 is disposed in proximity to the wall 14^a of the cutout 8 and is provided with spaced rearwardly extending parallel bearing members 18 which project through the walls 14, 14^a in the aileron 9. Revolubly mounted in the members 18 is a shaft 19 which is fixed to aileron 9 and has its ends mounted in bearings 20 secured to the side walls 21 of the cutout 8. The members 18 in connection with the shaft 19 and bearings 20 couple the aileron 9 with the wing body 4 and permit it to be angularly adjusted relative to said wing body. The walls 14, 14^a are disposed at an inclination corresponding substantially to the inclined trailing edge of the wing-structure.

The wing body 3 is formed in its top rearwardly of the wall 14^a of the cutout 8 with a set of spaced aligned openings 22 substantially at the lengthwise center of the wing-structure. Extending through each opening 22 is an adjusting rod 23 pivotally connected at its rear end as at 24 to an upstanding lug 25 fixed upon the top of the aileron 9. The forward end of the rod 23 is pivotally connected as at 26 to a crank 27 fixed on a rotatable torque tube 28 carried by the wing body 3, extending through the spars of the latter and into the body of the airship and con-

nected to any suitable means, not shown, for rotating it.

The brace member 16 is disposed at an inclination with respect to the brace member 17 and merges into the latter inwardly of the outer end of such member 17. Struts 29 are interposed between the brace members 16, 17. Connected to and extending forwardly from the brace member 17 is a set of spaced bearings 30 for a purpose 10 to be referred to.

Formed integral with, arranged over and merging at its sides into the top of the wing body 3, as well as extending forwardly from the leading edge of the wing-structure 2 is a stream-lined 15 housing 31 disposed in transverse relation with respect to the wing-structure. The housing 31 includes a fixed rear wall 32, a bottom 32^a which extends rearwardly beyond wall 32 and is fixed to brace member 17. The housing includes a 20 fixed front wall 33 provided with an axial opening 34 and a rearwardly extending tubular bearing 35 which is flush with the opening 34. Arranged within the housing, as well as being connected thereto is a partition 36, having an axial 25 opening 37 and a rearwardly extending tubular bearing 38 which is flush with the opening 37. The wall 32 and a partition 36, in connection with the bottom 32^a and a part of the top of housing 31 provide a chamber 39 for containing a 30 body of oil or lubricant which is supplied to chamber 39 through a normally closed opening 39^a. Leading from the interior of the body of the airship and extending through one side of the latter is a pair of spaced struts 40, 41 which 35 extend into housing 31 and merge into one side of an elongated tubular bearing 42. The struts 40, 41 constitute a hanger for the bearing 42 and said struts between the housing 31 and the body of the airship are enclosed by a casing 43. 40 Mounted in the bearings 35, 38 and 42 is a driving shaft 44 for a propeller 45. The shaft 44 extends forwardly from the end wall 33 of housing 31 and has keyed thereon, as at 46 the hub 47 of the propeller 45. The blades of the latter are indicated at 48 and extend from the hub 47. The latter at its forward end is mortised as at 49 and seated against the mortise is a hub cap 50. Holdfast means 51 are employed for fixedly securing the cap 50 to the hub 47. The shaft 44 45 at its forward end extends into the cap 50 and carries a washer 52 and a holding nut 53. Washer 52 abuts against the hub 47 and the nut 53 has threaded engagement with the reduced end 54 of the shaft. The nut 53 abuts washer 52. 55 Arranged and operating in the chamber 39 is a driving gear 55 of bevelled form for operating a bevelled gear 56 on the inner end of the shaft 44. The gear 56 is arranged within chamber 39. The gears 55, 56 operate in the oil supplied to the 60 chamber 39. The gear 55 is carried on one end of a power transmitting shaft 57 and extends into the chamber 39 through one side of the housing 31. The said side of housing 31 carries a bearing 58 for shaft 57. The latter is also 65 mounted in the bearings 30 which extend from the brace 17.

The wing-structures of each set are arranged in staggered relation thereby disposing the propellers of the set in a like relation, and with 70 reference to Figures 3 and 4, the driving means is illustrated for the staggered arrangement of each of the sets of propellers. One set of propellers is generally indicated at A and the other set at B. The motor for driving the propellers 75 of the set A is indicated at C. The motor for

driving the set of propellers B is indicated at D. The main line shaft extending from each motor is indicated at E and it has associated therewith what may be termed an auxiliary line shaft F driven from line E by a gearing G. The shafts 5 E and F are arranged in spaced relation. The line shaft E drives the propellers H of a set and the line shaft F drives the propellers I of the same set. The operating means for each of the propellers H consists of a bevelled gear J on the line shaft E for operating a bevelled gear K carried on the lower end of shaft 57. The diameter of bevelled gear K is less than that of gear J whereby a reduction in drive is obtained. The operating means for each of the propellers I 15 consists of a bevelled gear L mounted on line shaft F and a bevelled gear M on the shaft 57. The gear M is of greater diameter than gear L whereby a reduction in drive is obtained. With respect to one of the propellers H of each set, a 20 reversing means for the drive thereof is employed in connection therewith for the purpose of braking, when landing. In this connection the gear K of such propeller is keyed on shaft 57 and is carried by a collar N to which is attached a gear O of the same diameter as and bodily moves with the gear K when a reverse drive is desired. Shifting means for the collar N is indicated at P and is so arranged that the gear K may be meshed with the gear J or the gear M meshed 30 with the latter. When gear O is in mesh with gear J the propeller is reversely driven with respect to the direction in which the other propellers drive, but when gear K is in mesh with gear J the propellers operate in the same direction as the other propellers. 35

The length of each wing-structure is to be determined by the proper clearance at the hull or body of the vehicle. The area of each wing-structure is to be determined by wind tunnel tests 40 or computed from airfoil data. The controls are to be operated by cables throughout the ship.

What I claim is:

1. In an air ship, a wing, a wing, a stream-lined housing disposed transversely of, projecting forwardly from and merging into the top of the wing, said housing including front and rear walls and a partition correlating with said walls to form the housing with a bearing chamber and an oil chamber, said partition and front wall being 50 formed with aligned bearings, a propeller shaft mounted in said bearings and extended outwardly from said front wall, driving means for said shaft arranged in said oil chamber, a propeller including a hub fixed on the shaft and abutting 55 and flush with said front wall, means carried by the shaft and coacting with said driving means for securing the hub against said front wall, an enclosure connected to the hub for the said means carried by the shaft, and a fixed suspended bearing arranged in said bearing chamber for said shaft.

2. In an air ship, a wing having inherent parts providing a housing disposed transversely thereof, said housing being formed with a leading and a trailing chamber, each having a leading and a trailing wall, said housing being formed in one side thereof with a leading and a trailing opening communicating respectively with said leading and trailing chambers, the said walls of the leading chamber being provided with aligned bearings, a propelling shaft mounted in said bearings extended respectively from the walls of the leading chamber and carrying a bevel gear positioned in the trailing chamber, means extending through 70 75

the trailing opening into the trailing chamber for operating said gear to drive said shaft, a propeller fixed to the shaft and including a hub abutting the leading wall of the leading chamber, a fixed bearing for said shaft arranged within the leading chamber, and means extending through said leading opening into said leading chamber for suspending said fixed bearing.

3. In an air ship, a wing having inherent parts providing a housing disposed transversely thereof, said housing being formed with a leading and a trailing chamber, each having a leading and a trailing wall, said housing being formed in one side thereof with a leading and a trailing opening communicating respectively with said leading and trailing chambers, the said walls of the leading chamber being provided with aligned bearings, a propelling shaft mounted in said bearings extended respectively from the walls of the leading chamber and carrying a bevel gear positioned in the trailing chamber, means extending through the trailing opening into the trailing chamber for operating said gear to drive said shaft, a propeller fixed to the shaft and including a hub abutting the leading wall of the leading chamber, a fixed bearing for said shaft arranged within the leading chamber, means extending through said leading opening into said leading chamber for suspending said fixed bearing, said wing including a fixed brace rearwardly of said trailing chamber, and means carried by said brace for supporting the means extending into the trailing chamber.

35 into the trailing chamber.
4. In an air ship, a wing having inherent parts
providing a housing disposed transversely there-
of, said housing being formed with a leading and

a trailing chamber, each having a leading and a trailing wall, said housing being formed in one side thereof with a leading and a trailing opening communicating respectively with said leading and trailing chambers, the said walls of the leading chamber being provided with aligned bearings, a propelling shaft mounted in said bearings extended respectively from the walls of the leading chamber and carrying a bevel gear positioned in the trailing chamber, means extending through the trailing opening into the trailing chamber for operating said gear to drive said shaft, a propeller fixed to the shaft and including a hub abutting the leading wall of the leading chamber, a fixed bearing for said shaft arranged within the leading chamber, means extending through said leading opening into said leading chamber for suspending said fixed bearing, and means connected to one side of the housing for enclosing the means extending into the leading chamber.

WILLIAM WIESE.
